United States Patent Office

Des. 198,018
Patented Apr. 21, 1964

198,018

TOILET OR SIMILAR ARTICLE

Ronald Wadsworth, Pasadena, Calif., assignor to Norris-Thermador Corporation, Los Angeles, Calif., a corporation of California

Filed July 9, 1963, Ser. No. 76,004

Term of patent 14 years

(Cl. D4—5)

FIG. 1.

FIG. 2.

FIG. 3.

FIG. 4.

FIG. 5.

FIG. 7.

FIG. 6.

FIGURE 1 is a front perspective view of a toilet or similar article embodying my design with the cover in closed position.

The portions shown in broken lines are included for illustrative purposes only.

I claim:

The ornamental design for a toilet or similar article, as shown and described.
